United States Patent Office

Des. 191,792
Patented Nov. 21, 1961

191,792

EXERCISING MACHINE

James Maratta, Pelham, N.Y., assignor to Physio-Health,
Inc., Pelham, N.Y., a corporation of New York

Filed May 9, 1961, Ser. No. 65,135

Term of patent 14 years

(Cl. D34—5)

I claim:

The ornamental design for an exercising machine, as shown.
